UNITED STATES PATENT OFFICE

153,561

DESIGN FOR A PAIR OF SUNGLASSES

William L. Seidel, Wyomissing, Pa., assignor to
Willson Products, Inc., Reading, Pa., a corpora-
tion of Pennsylvania

Application November 23, 1948, Serial No. 149,780

Term of patent 14 years

(Cl. D57—1)

To all whom it may concern:

Be it known that I, William L. Seidel, a citizen of the United States, residing at Wyomissing, in the county of Berks and State of Pennsylvania, have invented a new, original, and ornamental Design for a Pair of Sunglasses, of which the following is a specification, reference being had to the accompanying drawing, forming part thereof.

Fig. 1 is a top plan view of a pair of sunglasses, showing my new design.

Fig. 2 is a front view of the same.

I claim:

The ornamental design for a pair of sunglasses, substantially as shown.

WILLIAM L. SEIDEL.
